UNITED STATES PATENT OFFICE.

ELICK BERLINGER, OF NEW YORK, N. Y.

RAILWAY PORTABLE COUCH.

No. 918,266.

Specification of Letters Patent. Patented April 13, 1909.

Application filed May 11, 1908. Serial No. 432,028.

To all whom it may concern:

Be it known that I, ELICK BERLINGER, a citizen of the United States, and a resident of the city of New York, borough of Manhattan, in the county and State of New York, have invented a new and Improved Railway Portable Couch, of which the following is a full, clear, and exact description.

My invention relates to couches, and more particularly couches of such type as to be readily carried around by hand and useful to passengers upon railways, as a means for enabling a traveler to recline while aboard a car.

Reference is to be had to the accompanying drawings forming a part of this specification, in which similar characters of reference indicate corresponding parts in all the figures.

Figure 1 is a side elevation partly broken away and showing my improved couch connected with an ordinary car seat of the kind used upon passenger coaches, the couch being in proper position to enable the passenger to recline upon it; Fig. 2 is a reduced plan view of the couch complete and ready for use; Fig. 3 is a side elevation showing the two parts of the couch as laid one upon the other, so as to be readily carried or used for any other purpose than for enabling the passenger to recline, and Fig. 4 is a detail showing one of the side plates and one of the bolts slidable relatively thereto.

Two cushions 4, 5 are provided respectively with wooden frames 6, 7, and mounted upon the frame 6 are feet 8 upon which the couch partially rests, as will be understood from Fig. 1. The frame 7 is provided with hooks 9 for partially supporting the end of the couch opposite the feet 8. The frames 6, 7 are provided with side plates 10, 11, said plates having eyes 12, 13 secured thereto. Bolts 14, each provided with a head 15 and with an aperture 15^a, are slidably mounted in the eyes 12 and movable endwise in the general longitudinal direction of the frame 6. Pins 16 pass directly through the bolts 14, which are provided with the apertures 16^b, 16^c for receiving the pins 16. The plates 10, 11 are secured to the frames 6, 7 by screws 17, 18.

The pins 16 are used for two purposes, in-

dicated respectively in Figs. 2 and 3. When 55 the bolts 14 are in the position indicated in Fig. 2, the pins 16 extend through the bolts and through the side plates 11. When, however, the bolts 14 are withdrawn, as indicated in Fig. 3, so as to disconnect the cushions, the pins 16 extend through the bolts 14 and through the side plates 10. In this way, the pins 16 are prevented from hanging down or getting in the way, and yet are at all times handy for the purpose of connecting the cushions together. The pins 16 are carried by chains 19, these chains being connected to the outer eyes 12. The car seats are shown at 20, 21, and are provided rearwardly at their bottoms with foot railings 22. 70

My invention is used as follows: The traveler places the cushions 4, 5 end to end, withdraws the pins 16, and grasping the heads 15 pushes the bolts 14 endwise so that they pass into the eyes 13. The passenger next places the pins 16 in the position indicated in Fig. 2, so that they extend through the bolts 14 and also through the side plates 11. The two cushions 4 and 5 are now held rigidly together, and together constitute a couch, as will be understood from Fig. 1. The passenger next places the couch in the position indicated in Fig. 1, so that the hooks 9 engage the back of one car seat and the feet 8 extend beneath the rear of the next car seat 85 forward. The passenger may now recline upon the couch thus constituted, resting his feet, if need be, upon the foot rail 22 of the seat 20.

When the couch is not in use it may be 90 taken apart and the two cushions placed together, as indicated in Fig. 3. These two cushions may be used independently or together for many purposes. For instance, they may be laid upon one of the seats 20, 95 21 and employed as a pillow.

Having thus described my invention, I claim as new and desire to secure by Letters Patent:

The combination of a cushion provided 100 with a convex surface, and further provided with hooks for engaging a car seat, a second cushion provided with a concave surface and further provided with feet for resting upon a floor, and mechanism including sliding 105 bolts for connecting said cushions together end to end so as to prevent the bending of said cushions relatively to each other in

either direction, and to hold the convex surface of said first-mentioned cushion and the concave surface of said second-mentioned cushion practically in alinement, thereby forming a continuous member one end of which presents a concave surface and the other end of which presents a convex surface.

In testimony whereof I have signed my name to this specification in the presence of two subscribing witnesses.

ELICK BERLINGER.
